CLAIM

The ornamental design for a baby play nest, as shown and described.

DESCRIPTION

FIG. 1 is a perspective view of a baby play nest having our design;

FIG. 2 is a right side view the baby play nest of FIG. 1;
FIG. 3 is a left side view of the baby play nest of FIG. 1;
FIG. 4 is a rear view of the baby play nest of FIG. 1;
FIG. 5 is a front view of the baby play nest of FIG. 1;
FIG. 6 is a top view of the baby play nest of FIG. 1;
FIG. 7 is a bottom view of the baby play nest of FIG. 1;
FIG. 8 is a perspective view of a base portion of the baby play nest of FIG. 1;

FIG. 9 is a right side view the base portion of FIG. 8;
FIG. 10 is a left side view of the base portion of FIG. 8;
FIG. 11 is a rear view of the base portion of FIG. 8;
FIG. 12 is a front view of the base portion of FIG. 8;
FIG. 13 is a top view of the base portion of FIG. 8;
FIG. 14 is a bottom view of the base portion of FIG. 8;
FIG. 15 is a perspective exploded view of the baby play nest of FIG. 1;

FIG. 16 is a perspective view showing a first example of the usage of the baby play nest; and,

FIG. 17 is a perspective view showing a second example of the usage of the baby play nest.

The broken lines in the drawings depict environmental features of the baby play nest that form no part of the claimed design. The shade lines in the drawings show contour and not surface ornamentation. All other surface(s) or portion(s) of the baby play nest not shown in the figures or otherwise described in the specification form no part of the claimed design.
